PRESSER-FOOT-LIFTING MECHANISM FOR SEWING-MACHINES.

1,241,733.

Specification of Letters Patent.

Patented Oct. 2, 1917.

Application filed June 23, 1914. Serial No. 846,726.

To all whom it may concern:

Be it known that I, PARK A. HERR, a citizen of the United States, residing at Saybrook, in the county of Union and State of New Jersey, have invented certain new and useful Improvements in Presser-Foot-Lifting Mechanisms for Sewing-Machines, of which the following is a specification, reference being had therein to the accompanying drawings.

This invention relates to presser-foot lifting mechanisms for sewing machines, being especially adapted for use in connection with machines for sewing heavy work, such as harness, belting and the like, in which the work is fed by lateral movements of the needle.

The present improvements comprise means whereby the presser-foot may be automatically lifted above the work immediately prior to and during each effective movement of the sewing machine feeding mechanism, the presser-foot being intermittently lifted a uniform distance above the work, regardless of varying thicknesses thereof.

The presser-bar clamping and lifting elements consist of a collar loosely fitted upon the endwise-movable presser-bar of the machine and having a laterally-projecting split portion, each section of the said split portion being a thickened wall merging into the relatively-thin main curved wall of the collar. The collar is embraced by the yoke of a clamping-lever, each arm of the yoke being fulcrumed upon the base of the collar on a line lengthwise of, and intersecting, one of the thickened walls of the split portion; and a contact-stud at the rear of the yoke abuts the opposite and spaced wall of the split portion. When the lever is lifted, a clamping force is applied to the split portion of the collar in opposite directions, and the sections thereof are forced toward each other; with the result that the entire inner curved area of the collar is compressed about the presser-bar. The succeeding lift of the lever elevates both the collar and the presser-bar clamped thereby.

The lifting means for the clamping-lever comprises a lifting-lever pivotally mounted at one end upon the overhanging arm of the machine, and intermittently pressed upward by an endwise movable post actuated by a rotary cam-disk on the driving shaft of the machine.

In a modified form of the improvements, one arm of the clamping-lever yoke is formed as a bell-crank and is adapted to act upon one section of the split portion of the collar through the intermediary of a link having a bent-end which supports the contact-stud. Each form of the improvements is such that the collar is compressed upon the presser-bar by a force which decreases its normal diameter, the force being applied at opposite sides of the enlarged split portion of the collar and in a plane exterior the periphery of the bar. By the aforesaid arrangement, the twist or torsion imposed upon the presser-bar of a sewing machine by known devices of the present character is largely reduced, and therefore the bar is not bent under the repeated action of the lifting-mechanism.

In the drawings, Figure 1 is a perspective view of the improvements as applied to a sewing machine. Fig. 2 is a top plan view of the clamping-collar and the parts immediately connected therewith. Fig. 3 is a perspective view of the modified form of the clamping-collar, in which a link is disposed intermediate one yoke arm of the lifting-lever and a lug projecting from one section of the split portion of the collar; and Fig. 4 is a similar view from the rear of the clamping-collar. Fig. 5 is a perspective view of the collar detached from its clamping elements.

In Fig. 1 of the drawings is illustrated, by dotted lines, part of the overhanging arm A of a sewing machine, in the head of which is journaled the usual endwise-movable presser-bar 1, supporting the adjustable presser-foot 2. A shaft 3, journaled in the overhanging arm, is provided with a rotary cam-disk 4 which is employed to exert a lifting pressure upon the presser-bar through the intermediaries hereinafter described.

In practice, the presser-bar is spring-pressed downwardly into engagement with the work resting upon the work-plate of the machine, and is elevated above the work during the work feeding action. To this end, a clamping-collar 5 is loosely fitted upon that portion of the presser-bar which projects above the overhanging arm A. The collar is formed with a lateral projection, which is split to form two sections a, b, having thickened walls which merge into

the relatively-thin main curved wall of the collar. The increased thickness, and hence weight, of the separated sections or end-portions *a*, *b*, of the split collar facilitates compression of the same against the spring-action of the connecting circular wall, as will be understood without further explanation.

10 The collar 5 is embraced by the yoke of a clamping-lever 7, the arms of the yoke being fulcrumed by means of stud-screws 8, upon the enlarged base 5^x on a line extending lengthwise of, and intersecting, the section *b*. At the rear of its yoke, the clamping-lever is provided with an upwardly extending lug 7^x apertured to receive the contact-screw 9, which abuts section *a*. It will be seen that upward movement of the clamping-lever will apply a compressive force on opposite sides of the split portion of the collar, the sections *a* and *b* being moved toward each other, with the result that a circumferential tensile stress is imposed upon the collar and the entire inner curved area thereof is compressed about the presser-bar. The split collar 5 may also be considered as a flexible strap substantially surrounding the presser-bar 1 and having two relatively movable end-portions *a*, *b*, disposed at one side of the presser-bar 1. The clamping-lever 7 acts to force the end portions of the strap 5 toward each other thus causing said strap to grip the bar with substantial uniformity circumferentially thereof.

15 20 25 30 35 40 45 50 55 60 65 70 75 80 85 90 95 100 105 110 115 120 125 130

The lifting device for the clamping-lever consists of a lifting lever 10 fulcrumed at one end by means of stud-screw 11 upon the overhanging arm A of the machine, and at its opposite end provided with opposed upwardly extending guide-walls 12 forming a U-shaped seat for the end of the clamping-lever. Intermediate its ends, the lifting-lever rests within a transverse channel 13^x formed in the upper end of a post 13 endwise movable within a suitable bearing provided in the overhanging arm A. At its lower end the post 13 is provided with a roller-stud 14 adapted to be engaged by the periphery of the raised cam surface 15 of rotary cam-disk 4. The cam imparts an intermittent movement to the lifting-lever. In one stage of its movement, the lifting-lever turns the clamping-lever 7 upon its fulcrum-studs to clamp the collar 5 upon the presser-bar; and in a second stage of its movement the lifting lever elevates the presser-bar to maintain the presser-foot above the work during the advance of the work feeding element of the machine. Immediately after the feeding movement has been imparted to the work, the post rides off the cam-surface of the disk 4 and the presser-bar clamping elements are released. A spring 16, having one end secured upon the overhanging arm A and its opposite end

resting upon a pin 17 carried by the collar 5, serves to move the latter downwardly into its initial position.

A modified form of the improvements is illustrated in Figs. 3, 4 and 5 of the drawings. In the said modification, one arm 18 of the clamping-lever yoke is formed as a bell-crank and is connected, by means of pivotal-stud 19, with one end of a link 20. The opposite bent-end of link 20 is provided with a contact-screw 21 which abuts the face of a lug 22 projecting from section *a* of the split portion of collar 5. In its action, the modified form of the clamping-lever is similar to the form illustrated in Figs. 1 and 2 of the drawings, its leverage, however, being increased by the use of the link 20.

It will be understood that any suitable lifting means may be employed for the clamping-lever, and that various modifications, in addition to those herein shown and described, may be made, within the scope of the invention.

Having thus set forth the nature of the invention, what I claim herein is:—

1. In presser-foot lifting mechanism for sewing machines, the combination with a presser-bar, of a collar loosely fitted upon said presser-bar, said collar being split at one point circumferentially thereof, thereby defining two relatively movable portions, and being continuous at all other points circumferentially thereof, whereby it may resist a circumferential tensile stress, means acting on said portions of the collar to force them toward each other, thereby causing said collar to grip the bar, said means acting subsequently to lift the bar.

2. In presser-foot lifting mechanism for sewing machines, the combination with a presser-bar, of a split collar loosely fitted upon said presser-bar, means acting upon the portions of said collar adjacent said split with a force directed in a plane spaced from said presser-bar to draw said collar tightly about said presser-bar, said means acting subsequently to lift the bar.

3. In presser-foot lifting mechanism for sewing machines, the combination with a presser-bar, of a vertically movable split collar loosely fitted upon the presser-bar, lifting means adapted to decrease the normal diameter of said collar, said lifting means acting upon the collar with a force directed in a plane spaced from the presser-bar.

4. In presser-foot mechanism for sewing machines, the combination with a vertically movable collar adapted to be loosely fitted upon the presser-bar of a sewing machine and formed with a laterally extending split portion affording circumferentially spaced sections, of a clamping lever fulcrumed upon one section of said split portion of the collar and having a member adapted to apply a force to the opposite

section thereof directed toward the first mentioned section in a plane spaced from the axis of the presser-bar, whereby said collar is caused to securely grip the presser-
5 bar.

5. In presser-foot lifting mechanism for sewing machines, the combination with a presser-bar, of a split collar in the form of a flexible strap substantially surrounding
10 said presser-bar and having two relatively movable end-portions disposed at one side of the presser-bar, means for forcing the end-portions of said strap toward each other, thereby tightening said strap about
15 the presser-bar, said means acting subsequently to lift the bar.

6. In presser-foot lifting mechanism, the combination with a collar adapted to be loosely fitted upon the presser-bar of a
20 sewing machine and formed with a laterally extending split portion affording spaced sections, of a clamping-lever formed with a yoke embracing said collar, means for piv-

otally connecting the arms of said yoke to the collar on a line extending lengthwise of
25 one of said spaced sections, and a contact member carried by the lever and adapted to engage the opposite spaced section.

7. In presser-foot lifting mechanism, the combination with a collar adapted to be
30 loosely fitted upon the presser-bar of the sewing machine and formed with a laterally extending split portion affording spaced sections, of a lever fulcrumed upon one of
35 said spaced sections, and a link connected with said lever and provided with a contact member adapted to engage the opposite spaced section.

In testimony whereof, I have signed my name to this specification, in the presence of
40 two subscribing witnesses.
